UNITED STATES PATENT OFFICE.

BENJAMIN CHAMBERS, OF LODGE, VIRGINIA.

MOLD FOR CASTING COMPOSITION HAND-STAMPS.

SPECIFICATION forming part of Letters Patent No. 713,961, dated November 18, 1902.

Application filed June 9, 1902. Serial No. 110,803. (No model.)

To all whom it may concern:

Be it known that I, BENJAMIN CHAMBERS, a citizen of the United States, residing at Lodge, in the county of Northumberland and 5 State of Virginia, have invented certain new and useful Improvements in Molds for Casting Composition Hand-Stamps; and I do hereby declare the following to be a full, clear, and exact description of the invention, such 10 as will enable others skilled in the art to which it appertains to make and use the same.

My present invention has for its object to provide an improved mold which is designed more particularly for casting composition 15 blocks to be used in making hand-stamps and whereon any desired letters or characters, such as the name of a post-office, may be embossed in the simplest and most convenient manner.

20 To these ends my invention consists, essentially, of a mold formed, preferably, of two parts or sections, the lower part or section whereof is provided with an opening extending entirely through the same and wherein 25 intaglio or other dies are inserted from the bottom of said section, a plain or ornamental margin extending around the upper edges of the opening adjacent to the inserted letters or characters and the upper part or section of 30 the mold being adapted to fit upon the lower section and provided with an opening which registers with the outside edge of the marginal lines surrounding the opening in the lower section, all as will be hereinafter fully 35 described, and pointed out in the claim.

In order that my invention may be readily understood, I refer to the accompanying drawings, in which—

Figure 1 represents a vertical longitudinal 40 section of a mold constructed in accordance with my invention; Fig. 2, a top plan view of the lower section thereof with the type or dies in position therein; Fig. 3, a perspective view of the composition block formed by said mold, 45 and Fig. 4 a sectional view of a modification of my invention.

Similar letters of reference occurring on the several figures of the drawings indicate corresponding parts.

50 In carrying out my invention the mold may

be made in any desired size or shape and the lower part or section A thereof provided with an opening B, which extends entirely through the same. This opening is preferably rectangular in shape and is provided with a 55 plain or ornamental margin or border adjacent to the edges of said opening at the top. The intaglio dies C are fitted into this opening by turning the section A upside down, so that when in position the faces of the dies or 60 type rest level with the upper edges of the inclosing margin or border. The lower section may, however, be formed of two parts or sections, as shown in Fig. 4 of the drawings, in which event the lower part D is formed 65 with a recess or opening extending only a short distance into the same and the upper part having an opening extending entirely through the same in such manner that the combined openings are of such depth as to 70 accommodate the height of the dies or type, so that their upper edges will rest level with the surrounding margin. The upper portion E of the mold is adapted to rest upon the lower section in such manner that the opening 75 therein registers with the outside edge of the marginal lines or border upon the upper surface of the lower section. The parts or sections of the mold are held together in proper position by suitable pins F in one 80 section entering corresponding openings in the opposite section, or other equivalent means may be employed for accomplishing the same purpose.

In the operation of my invention, the parts 85 being in their normal position, a composition composed of melted glue and glycerin or its equivalent is poured into the opening in the upper section, and when the same cools and hardens the upper section is lifted, and the 90 composition block thus formed, with the desired letters or characters upon the same, is pushed out from the opening and the operation continued as before. In this manner the blocks may be made very economically 95 and the type or dies readily changed to produce any desired name or characters, thus obviating the expense of cutting or engraving the letters or characters upon the lower section, as in the usual manner.

Having thus described my invention, what I claim as new, and desire to secure by Letters Patent, is—

As a new article of manufacture, a mold for casting composition hand-stamps, consisting of upper and lower parts, the upper part having an opening to receive the composition of matter of which the stamp is to be made, the lower part having an opening therethrough

to receive and hold removable type, and the type in such opening, all substantially as specified.

In testimony whereof I affix my signature in presence of two witnesses.

BENJAMIN CHAMBERS.
